METHOD OF PRODUCING NONRAVEL KNITTED FABRIC

Oskar Sauer, Philadelphia, Pa.

Application March 4, 1936, Serial No. 66,984

2 Claims. (Cl. 66—96)

This invention relates to non-ravel knitted fabrics, as well as to methods of producing such fabrics.

My invention is directed in part toward the provision of a knitted fabric having the characteristics of plain knitted fabrics as regards smoothness, appearance and elasticity, but which will resist running in the event that the yarn is ruptured at any point therein; and which is moreover susceptible of production in sheer weights for hosiery and the like.

Another object of my invention is to provide a simple method whereby a non-ravel fabric having the above characteristics can be readily produced, particularly on flat knitting machines of the "Cotton" type with lace bar attachments, such as are ordinarily used in the production of full fashioned hosiery and the like.

I am aware that non-ravel fabrics have been produced heretofore on knitting machines of the type referred to by lateral transfer of predetermined loops between wales, but this not only resulted in distortion of the fabrics, but detracted greatly from their elasticity, so that they were not altogether satisfactory for stockings and the like. The above mentioned drawbacks are absent in my improved fabric, wherein as herein-after more fully explained, the shanks of normal loops in one course of the knitting occupy alternate wales of the fabric and are embraced by anchorage loops of an adjacent course in intermediate wales; and wherein the shanks of normal loops of another course occupying the intermediate wales of the fabric are embraced by anchorage loops of the first mentioned course. Also, as hereinafter more fully disclosed, my improved fabric is producible by forming the anchorage loops in alternate wales during the knitting of one course and releasing them over held normal loops of a previously formed course in the same wales, while concurrently forming normal loops in intermediate wales of the fabric; then during knitting of a second course, forming anchorage loops in the intermediate wales and releasing them over held normal loops of the first mentioned course while forming normal loops of said second course in the alternate wales of the fabric; and by continuously repeating this cycle.

In the drawings, Fig. I is a diagrammatic view showing the texture of my improved non-ravel knitted fabric.

Fig. II is a diagrammatic perspective view showing an arrangement of spring beard needles and cooperating presser points suitable to

the production of my improved fabric on a flat knitting machine of the Cotton type.

Figs. III—XIII are fragmentary cross sectional views of such a machine illustrating various steps in the knitting cycle by which my fabric is produced.

As delineated diagrammatically in Fig. I, my improved non-ravel knitted fabric comprises courses C¹ each having normal loops N¹ in spaced wales W¹, W¹ whereof the shanks are embraced by anchorage loops A² of an adjacent course C²; and anchorage loops A¹ in intervening wales W², W² embracing the shanks of normal loops N² of said respectively adjacent courses C². In the illustrated instance, it will be observed that the courses C¹ and C² are contiguous and consistently alternate throughout the fabric, and that the normal loops N¹ of the courses C¹ and the anchorage loops A² of the courses C² lie in alternate wales W¹, W¹; while the normal loops N² of the courses C² and the anchorage loops A¹ of the courses C¹ lie in intermediate alternate wales W², W². The fabric thus consists of repeats of the courses C¹ and C² in regular succession. A fabric of the described construction will obviously resist running by virtue of the binding action of the anchorage loops A¹, A² upon the normal loops N¹, N² in alternate courses and wales. In other words, a run originating in one course cannot spread to adjacent courses since such adjacent courses are formed from different lengths of the yarn, and furthermore since alternating courses are interengaged only by the anchorage loops with the shanks of normal loops of other courses. The fabric is moreover smooth, of single thickness as distinguished from rib fabric, undistorted, comparable in elasticity with plain fabric, and moreover susceptible of production in sheer weights for hosiery and the like.

One way in which the fabric can be readily produced on a flat knitting machine is shown in Figs. III to XIII, the machine having special needles 10, 10a with centrally-kinked barbs or beards 11, special knock-overs 12 with loop-detaining notches 13, and a lace bar having half as many presser points 15 as there are needles, with said points spaced by an interval double that of the needle spacing as shown in Fig. II. As shown for example in Fig. IV, the closing of the beard 11 of a needle 10 will result in the formation of two vertically-spaced eyes for a purpose which will be readily understood from further description. The sinkers indicated at 16 in Figs. III—XIII are arranged to slide as usual in transverse grooves of a sinker head 17 which

provides the ledge 18 for closing the needle beards 11 in the well known manner.

In Fig. III, the needle 10 and the cooperating point 15 are fully elevated and the sinker 16 fully retracted while the yarn Y is being laid for a course C². In Fig. IV, the sinker 16 is advanced, the needle 10 descending with its beard 11 closed by the point 15, and with a new loop A² engaged in the lower eye of said needle and being drawn down through a previously formed normal loop N¹ of a course C¹ in a wale W¹, said loop N¹ being supported at this time by a shorter nib of the knock-over 12. In Fig. V, the sinker 16 is retracted, the needle 10 and the point 15 lowered, with the newly-drawn anchorage loop A² at the level of the notch 13 of said knock-over. In Fig. VI, the knock-over 12 and the sinker 16 have been advanced to hold down the loops A² and N¹, while the needle 10 and the point 15 are rising, 10 the loop A² being detained in the notch 13 of said knock-over, and the loop N¹ being detained by the sinker. In Fig. VII, the needle 10 and the point 15 are again descending, with the loop N¹ engaged in the lower eye of said needle while the needle 15 beard 11 is closed over said loop, and with the point 15 penetrating the loop A². In Fig. VIII, the needle 10 is fully lowered with the point 15 separated laterally therefrom, and with the loop N¹ in the upper eye of said needle, knock-over 30 12 being at this time retracted, but the sinker 16 being still in advanced position. In Fig. IX, the point 15 is rising alone and about to release the loop A² for casting of the same over the top of the needle 10, said needle, the knock-over 12, 35 and the sinker 16 remaining substantially in the same positions which they occupied in Fig. VIII. In Fig. X the point 15 is still rising after having cast the loop A², and the needle 10 about to follow with the loop N¹ engaged in its upper eye. 40 While the above events are transpiring in the formation and release of anchorage loops A² of a course C² in the wales W¹ of the fabric, each of the needles 10a draws a single normal loop N² in a wale W² in the manner shown in Figs. XI, 45 XII and XIII. In Fig. XI, the needle 10a is fully elevated to take the yarn Y, the knock-over 12 being advanced and the sinker 16 retracted as in Fig. III. In Fig. XII the needle 10a is descending with the new loop N² of the yarn Y within 50 its upper eye, its beard being held closed in the usual way through contact with the presser ledge 18. In Fig. XIII, the needle 10a is shown lowered after having cast the old loop and is holding a now completed new normal loop N². 55 After the knitting of a course C² in the manner just explained, the point bar of the machine is shifted laterally to the position shown in dot and dash lines in Fig. III so that in the formation of a contiguous course C¹, the points 15 will cooperate with the intermediate needles 10a precisely as they cooperated with the needles 10 in the formation and casting of anchorage loops A¹ in the wales W² while the needles 10 at the same time form normal loops N¹ of such course C¹ in the 60 wales W¹. At the completion of the course C¹ the point bar is shifted laterally back to its original position in readiness for the knitting of another course C². This completes a knitting cycle which is continuously repeated throughout the 65 70 knitting of the fabric.

Any suitable means may be employed for actuating the needles, the presser points, knock-overs and the sinkers in the manner hereinbefore set forth to produce my improved non-ravel fabric.

Having thus described my invention, I claim:

1. The method of producing non-ravel fabric with needles having medially kinked spring beards which upon being closed afford vertically spaced eyes, by successive repetitions of a cycle which comprises closing the beards of alternate needles over newly laid yarn so that said yarn is confined in the lower eyes of such needles; depressing the needles so that anchorage loops are drawn by the alternate needles through previously formed normal loops on them to a level below the latter loops; holding the anchorage and the previously formed normal loops respectively at the different levels while the needles are being elevated to clear the beards of the alternate needles above the corresponding previously formed normal loops at the higher level; then again depressing the needles and incidentally closing the beards of the alternate needles over the previously formed loops on them to draw said loops down through the anchorage loops at the lower level and permitting casting of the latter loops over said alternate needles; then elevating the needles to take new thread; then forming from newly laid thread normal fabric loops on said alternate needles while anchorage loops are formed on the other needles in the same manner as aforesaid.

2. The method of producing non-ravel fabric on a flat knitting machine having needles with medially kinked spring beards which upon being closed provide vertically spaced eyes, cooperating sinkers, cooperating knock-overs with lateral loop detaining notches between the fabric supporting ledges and over-reaching nibs, a stationary beard pressing ledge, and a bar with a beard presser point at every other needle, by successive repetitions of a cycle which comprises forming loops around the shanks of the needles by advance of the sinkers upon newly laid thread; then depressing the needles so that the ends of the beards of alternate needles pass over the new loops and closing the beards of such needles by means of the presser points so that the newly engaged loops on them are confined to the lower eyes of said needles while being drawn through previously formed normal loops detained by the points on the nibs of the knock-overs and down to the level of the notches in the latter; then advancing the knock-overs for detainment within their notches of the newly formed loops on the alternate needles and at the same time advancing the sinkers over the previously formed loops; then elevating the needles sufficiently for clearance by the ends of the beards of the alternate needles of the previously formed loops; then again depressing the needles and closing the beards of the alternate needles over the previously formed loops by means of the presser points; then retracting the knock-overs so that as the needles continue their descent, the previously formed loops on the intermediate needles are drawn through the newly formed loops at the lower level; then elevating the presser points alone to release the new anchorage loops and permit them to be cast over the normal loops on the alternate needles; then elevating the needles to take new thread and shifting the presser bar to bring its points over the intervening needles in readiness to cooperate with them; then forming from the newly laid thread normal fabric loops on the aforesaid alternate needles in the usual way incident to which the beards of said alternate needles are closed by contact with the stationary presser ledge, while anchorage loops are formed on the remaining needles in the same manner as aforesaid.

OSKAR SAUER. 75
